Primary Examiner — David G Muller

Assistant Examiner — Christina Gabrielle Cosden

(57) **CLAIM**

We claim the ornamental design for a plate guard, as shown and described.

DESCRIPTION

FIG. 1 is a perspective view of a plate guard.
 FIG. 2 is a front side view of the claimed design.
 FIG. 3 is a rear side view of the claimed design.
 FIG. 4 is a left side view of the claimed design.
 FIG. 5 is a right side view of the claimed design.
 FIG. 6 is a top view of the claimed design; and,
 FIG. 7 is a bottom view of the claimed design.

1 Claim, 5 Drawing Sheets
